UNITED STATES PATENT OFFICE.

JAMES W. MURPHY, OF AKRON, OHIO.

BLOCK-SIGNAL SYSTEM.

1,094,918.

Specification of Letters Patent. Patented Apr. 28, 1914.

Application filed April 29, 1912. Serial No. 694,013.

To all whom it may concern:

Be it known that I, JAMES W. MURPHY, a citizen of the United States, residing at Akron, in the county of Summit and State 5 of Ohio, have invented a certain new and useful Improvement in Block-Signal Systems, of which the following is a specification.

The object of this invention is to provide 10 improved means of the kind stated that can be installed and maintained at small cost and whereby a signalman is prevented from manipulating his signal operating lever without the coöperation of the signalman at the next station.

My invention has for an important feature means including automatic electrically operated selective devices included in the main line whereby the signalman must operate his signal from danger or normal position to caution position or from caution to safe or clear position within a limited time, otherwise he is precluded from operating it at all except upon a fresh release from 25 the man at the distant station.

A further feature of the invention is that means are provided whereby the operation of the signal lever from danger position to caution position causes the breaking of the 30 circuit independent of an automatic breaking of the circuit at the automatic selector so that independent of such automatic breaking of the circuit the signalman cannot, even if he would, move the signal operating lever 35 in one movement from danger position to clear position. To move the signal from danger or normal through caution position to clear position therefore requires two distinct operations of the selector key by the 40 signalman at the distant station thus insuring ample time for the signalmen to consider the propriety and safety of their acts.

The invention is embodied in the apparatus and combinations of parts herein 45 shown and described, the features of novelty being pointed out in the appended claims.

In the accompanying drawings forming part hereof—Figure 1 illustrates diagrammatically, and in most respects conventionally, the parts and combinations of parts as I employ them in practice in connection with a telegraph line. Fig. 2 is a similar view showing the invention as used in connection with a telephone line. Fig. 3 is a 50 plan view of the controller. Fig. 4 is a front elevation of the selector key. Fig. 5 is an

end view of the same with parts broken out. Fig. 6 is a sectional view on the line V—V showing the selector key mechanism, the front plate being removed. Fig. 7 is a plan view of the telegraph key. Fig. 8 is an edge view of the same. Fig. 9 is a detail illustrating the signal and operating mechanism.

The portions of the diagram, Fig. 1, on each side of the line W—W illustrate the 65 apparatus and wiring at each of two adjacent stations designated for convenience X and Y. The apparatus or instruments and wiring at each of the two stations are substantially identical and the parts that correspond to each other at the two stations in the drawings are designated by like characters of reference, hence a description of the apparatus at one station will suffice for both.

In the views at 1 is an ordinary telegraph 75 relay and at 2 is a controller or rotary circuit breaker (see Fig. 3) having metallic closers *a* and *e* and *f*. At 3 is a telegraph key having contacts *c* and *b* and *k*.

Referring to Figs. 7 and 8 which illustrate the telegraph key the base 25 has mounted upon it the key lever 26 with a spring 27 for holding the telegraphing contacts separated as usual. The base is provided with the contact members *b*, *c* and *k* 85 insulated from the base and with a switch lever 28 having arms *b*¹, *c*¹ and *k*¹ which can be swung to close or open the contacts *b*, *c* and *k* as shown by full and broken lines, Fig. 7. In the normal position the 90 contacts *b* and *c* are closed. To permit manipulation of the key for the purpose of ordinary communication the lever 28 is moved to the position indicated by broken lines, Fig. 7, thereby breaking the contact at *c* 95 and making contact at *k*. The normal position of the parts shown in full lines is that for receiving messages and the selector operating impulses. For outgoing messages or operation the lever 28 is moved to the 100 broken line position.

At 4 is the selector key. This selector key which is shown in detail in Figs. 4 to 6 inclusive includes the code-wheel 30 having a shaft 30^a journaled in a frame 31, said code-wheel 30 having its rim provided with teeth and spaces, the teeth to act on a spring arm 32 having one of the contacts *n*. In connection with the code-wheel is a train of pinions and gears 33, 34, 35, 36, 37 and 38. 105 The shaft 33^a has a suitable spring 39 for propelling the train. The shaft 33^a is pro-

vided with a ratchet 33^b to engage a pawl 33^c held by a spring 33^d on said wheel 33 so that by turning the shaft 33^a in one direction the spring 39 of said wheel can be 5 placed under tension to rotate the wheel 33 in the opposite direction. The shaft 33^a at its front or exposed side is provided with finger pieces 40 for permitting the operation of said shaft 33^a. The shaft 33^a 10 is also provided with an arm 41 which holds the contact *m* closed and permits their separation when the shaft is turned to place the spring 39 under tension for an actuation of the code-wheel, said arm 41 being turned 15 away in a direction to permit the spring arm containing one of said contacts *m* to move away from the other. The actuation of the code-wheel is properly retarded by means of an ordinary ratchet 42 geared to 20 the operating train in connection with an escapement 43.

At 5 is the automatic selector having contacts at *h*. In practice I propose to use in connection with my equipment the selective 25 device commonly known in the market as the "Gill selector", but any selector device which is constructed to respond only to an arbitrary set or code of electrical impulses for effecting the temporary closing of a circuit will suffice. At *h* (Fig. 1) is represented the circuit closing contacts of such a device.

From the construction of the code-wheel, shown in Figs. 4 to 6, it will be plain that 35 when the selector key is actuated the necessary arbitrary electrical impulses will by the consequent operation of the code-wheel be sent through the automatic selector to effect its operation and the closing of the 40 contact *h* and that during a limited period, say thirty seconds, when that portion of the rim of the code-wheel between the points —*p*—*q*— is operating to hold the contact *h* closed the circuit of the electro-magnet 8 45 operating the latch lever will be closed thereby energizing said magnet and raising said latch lever and permitting the operation of the signal lever. Therefore it is during this period that the signalman at the 50 receiving station must operate his signal lever otherwise the parts of the automatic selector automatically return to normal position and render it impracticable for him to move his lever until the agent at the remote 55 station reoperates his selector key.

The signal 50 is of the ordinary three position kind and has any suitable connection with its operating lever 10. The lever 10 has hingedly connected with its lower end 60 a rod 10^a on which is secured a block 7 having notches 13 and 14 into which can fall the latching end of a gravity armature 12 operated by the electro-magnet 8 included in the local circuit B containing a battery 6. 65 When the latching armature or lever 12 en-

gages the notch 13 the lever 10 is in blocking position and is locked but when the said latching armature is in the notch 14 the lever is at "caution" position and cannot be moved to "clear" position except upon a 70 second operation of the selector key or a skilful manipulation of the telegraph key to send corresponding impulses. From its position in notch 14, however, the lever 10 can be moved reversely to notch 13 or the 75 blocking or danger-indicating position because of the inclined side of said notch 14. In the "clear" position of the lever 10 the latching end of the armature 12 rests upon the top of the block 7 at 14^a. 80

H is a local circuit conveniently energized by a portion of the battery 11 when the signal lever 10 is released; and said circuit can include an audible signal at 9 and a make-and-break at *g*, said make-and-break being 85 operated by the armature 12 to close the circuit H.

The main or outside line is designated A A. This line comes in through relay 1, and from the relay the line or conductor designated A passes through telegraph key 3, the contact *m* of automatic selector key 4, controller 2, selector 5 to ground G. The line A A also has a branch conductor F through contact *n* of automatic selector key 4. The 95 line F beyond key 4 is connected with a conductor E from contact *h*, said conductor E running to controller 2 and thence through battery 11 to ground at G.

It will be understood, of course, that appropriate casings with locks or both locks and seals for such parts as should not be tampered with will be provided. 100

The operation is as follows: The telegraph circuit, outgoing, from either station is or may be traced from ground G, through battery 11, to conductor E, through controller 2, to contact *h*. By moving the circuit breaker or lever of the telegraph key 3 to contact *h*, contact *c* is broken, permitting 110 telegraphic operation through conductor E and A through telegraph relay 1 and line A A. 115

The telegraph circuit, incoming, at either station is from line A A through telegraph relay marked 1, to telegraph key 3, through contact *b* to *c* (the lever 10 being in normal position) to *m* thence on conductor A through controller 2 to coils or magnets of selector 5 thence to ground G. The incoming lock release circuit at either station is 120 first through the automatic selector key of the sending station, then from the line A A through relay 1 on conductor A, to telegraph key 3, through contacts *b* and *c* to automatic selector key 4, through contact 125 *m* to conductor A, through controller 2 to selector 5 and ground G. The telegraph key of a sending station can be manipulated to produce a code like that of the automatic selector key and the operation of that selec- 130

tor key omitted but this can only be done by a skilful operator and one who has knowledge of the code or codes of the selector keys.

5 The selector upon receiving its code or selective impulses will cause contact *h* to close, thereby energizing conductor *B*, through battery *6*, through magnet *8*, and lifting armature latch *12* of lock thereby releasing block *7*, and permitting the controlling signal lever *10* to be moved. And the plane portion of the code wheel from notch *q* to notch *p* will hold the contact *n* closed, to thus maintain the signal lever in an un-
15 locked condition for a short period of time only, in which time the operator must operate his signal, if he operates it at all for that operation of the selector key. The lifting of armature *12*, closes contact *g*, closing circuit *H*, through battery *11*, and ringing bell *9*, thereby notifying the signal operator that lever *10* is released. In moving lever *10* from its normal position, which is that shown on the diagrams, contact *e* is broken
20 by controller *2* thereby opening conductor *A* and causing selector *5* to break circuit *B* at contact *h*. The breaking of circuit *B* due to the movement of lever *10*, or to contact *n* dropping in notch *p* of code wheel *30* (in
25 case the operator fails to move lever *10* within the limited time) and cutting out main line through selector *5*, controlling contact *h* permits armature *12* to drop into notch
30 14. To release block *7* from this new position the operation of the selector key must be repeated and while the lever *10* is held in its position at said notch 14.

The outgoing lock release at either station is thus: The automatic selector key, when
40 making and breaking the circuit at contact *n* causes contact *m* to be broken thus starting current at ground *G*, through battery *11* on conductor *E* through controller *2*, to conductor *F*, through contact *n* to line *A* *A*
45 and thence to the other signal office through the conductors in the same manner as described before to ground *G*.

It will be observed, for example, that in single track work and with the signals in
50 normal position and locked the signalman at one station *X* desiring to permit a train to proceed to the next station *Y* cannot place his own signal (at *X*) in "proceed" position until the signal (at *X*) is unlocked
55 electrically by the signalman at the next station *Y* and reversely. Further that while the signal is at a station (*X*) at "proceed" position the man at that station (*X*) cannot unlock the signal governing opposing movements at the next station (*Y*) and reversely. It is impracticable for two opposing block signals to be in the "proceed" position at the same time because when a signal lever
60 10 is moved from normal position the releasing circuit is broken thereby making it
65

impossible to operate the release at the other station. A "caution" block may be given and controlled by the signalman at the station in advance in the same manner as can be given a "clear" block. In this construction also a signalman is prevented from giving a train a "proceed" block without first co-operating with the signalman at the station in advance. From force of habit signalmen have often heretofore given trains a clear block when a "caution" block was the proper one. With my system this often occurring and accident-causing mistake is avoided.

From the construction shown it will be observed that the function of the controller is to prevent full operation of the signal lever and to permit telegraphing or communication by the sending or releasing agent to the lever operating agent but cutting off communication by the lever operating agent because his telegraph key is cut out of the circuit. Further the lever operating agent cannot release the signal controlling the opposing movement at the other station because the releasing key is cut out by the position of the controller. To permit both agents to communicate with each other both signal levers must be in danger position.

My invention can be used with great advantage on double-track roads either for following movements of trains or for positive blocking.

Where a block wire is already in use the invention can be used in connection with that wire and the expense of running a new wire therefor avoided. When used on a block wire there is no interference with the telegraph service for blocking trains. A block wire, however, should be cut at each block station. The invention can also be used in connection with telephone circuits, as indicated in Fig. 2 where 60 designates simplex or repeating coils and 61 telephones, the other parts being the same except that the telegraph key and relay are not shown.

The expense of installation is extremely small as compared with that of other systems and the cost of maintenance is trifling because the usual telegraph lineman can take care of the equipment along with his other work.

Among the advantages of the invention, it might be stated, that by the use of the selector key, herein described, for maintaining the circuit of the lock-operating means closed for a limited period of time, the signal-men at the two stations are compelled to operate their signals at the same time. That is to say, the signal-man at one station cannot advise the signal-man at the other station that he will release his signal, and permit him to operate his signal at some future time, as for instance, while or after the signalman at the first-mentioned station takes a rest, or

fails to take immediate notice of the signal. In other words, it places the responsibility of operation on two signalmen, acting at the same time, and hence one signalman cannot 5 operate a signal when he ought not to, but it is necessary that the two signalmen agree that the signal should be operated, and the position it should be operated to. Another important advantage of this arrangement is 10 that it prevents a signalman from pulling a signal through the second or "caution" position to the "clear" or third position. The breaking of the circuit is effective in this 15 phase of the practical operation of the signal.

What I claim is:

1. A block signal system, including in combination, signals at two stations, means for operating said signals, electrically controllable means for locking the signal-operating means, a line wire connecting the stations, two branch circuits leading from the line wire at each station, a source of current and a selector key in 20 one branch circuit at each station, and a selector and a circuit controller operated by the movement of the signal operating means in the other branch at each station, the selector at each station controlling the electrically 25 controlled signal-locking means at the same station, whereby the signal locking means at one station may be controlled by the selector key at the other station.

2. A block signal system, including in combination, signals at two stations, means for operating said signals, electrically controllable means for locking the signal-operating means, a line wire connecting the stations, two branch circuits leading from the line wire at each station, a source of current and a selector key in one branch circuit at each station, a selector and a circuit controller operated by the movement of the signal operating means in the other branch circuit at each station, the selector at each station controlling the electrically controlled signal locking means at the same station whereby the signal locking means at one station may be controlled by the selector key at the other station, and said selector keys each including means to keep the line circuit closed to maintain the signal locking means unlocked for a limited period of time and to automatically open the line circuit to permit said locking means to return to locking position upon failure of the operator to move the signal within said limited period of time.

3. A block signal system, including in combination, signals at two stations, means for operating said signals, electrically controllable means for locking the signal-operating means, a line wire connecting the stations, two branch circuits leading from the line wire at each station, a 60 source of current and a selector key

in one branch circuit at each station, and a selector and a circuit controller operated by the movement of the signal-operating means in the other branch circuit at each station, the selector at each station controlling the electrically controlled signal-locking means at the same station whereby the signal-locking means at one station may be controlled by the selector key at the other station, said selector keys having means for making and breaking the circuit for producing signal impulses through said selectors and for holding the circuit closed to maintain the signal-locking means in unlocked position for a limited period of time after 70 producing said signal impulses and to automatically open the circuit to permit the signal-locking means to return to locked position.

4. A block signal system, including in combination, signals at two stations, means for operating said signals, electrically controllable means for locking the signal-operating means, a line wire connecting the stations, two branch circuits leading from the line wire at each station, a source of current and a selector key in one branch circuit at each station, and a selector and a circuit controller operated by the movement of the signal-operating means in the other branch circuit at each station, the selector at each station controlling the electrically controlled signal-locking means at the same station whereby the signal-locking means at one station may be controlled by the selector key at 90 the other station, said selector keys having means for making and breaking the circuit for producing signal impulses through said selectors and for holding the circuit closed to maintain the signal-locking means in unlocked position for a limited period of time after 95 producing said signal impulses and to automatically open the circuit to permit the signal-locking means to return to locked position, after the expiration of said limited period of time, to thereby permit the operation of the signals within such limited period of time only.

5. A block signal system, including in combination, a line wire connecting two stations, a signal and signal operating device at each station, two branch circuits leading from the line wire at each station, means for locking the signal-operating devices in different positions, a local circuit at each station including means for operating said locking means, means included in one of said branch circuits at each station for controlling the operation of the local circuit at the other station through said line wire, said controlling means including a selector key and electro-magnetically operated devices in the other branch circuits controlled by said selector keys, to effect the unlocking of said signal locking means and maintain the same 115 120 125 130

in an unlocked position for a limited period of time, and to automatically open the circuit through said line wire to permit the locking means to return to locked position.

- 5 6. A block signal system, including in combination, a line wire connecting two stations, two branch circuits at each station, a signal and signal operating device at each station, means included in one of said branch 55 circuits at each station for controlling the locking of the signal operating device in different positions, means at each station included in the other of said branch circuits for controlling the locking and unlocking 60 10 means at each station through the line wire, said controlling means including means for maintaining the locking means in unlocked position for a limited period of time and for releasing and returning the locking means 65 15 to locked position.

7. A block signal system, including in combination, a line wire connecting two stations, two branch circuits at each station, a signal and signal operating device at each 25 station, electrically controlled means in one of said branch circuits at each station for controlling the locking of the signal operating device in different positions, means included in the other branch circuit at each 30 station for electrically controlling through the line wire the locking and unlocking of the signal locking means at each station, and a circuit breaker included in the last mentioned branch circuit and actuated by 35 the movement of the signal operating device for rendering inoperative the electrically controlled locking means during the movement of the signal operating device from one position to another.

40 8. A block signal system, including in combination, a line wire connecting two stations, two branch circuits at each station, a signal and signal operating means at each station, locks for said signal operating 45 means, electrically controlled means for operating said locks, including a selective device included in one of said branch circuits, at each station, a spring actuated key included in the other of said branch circuits, 50 at each station for controlling the operation of the selective devices at each station, said

keys having means coöperating with contacts to make and break the line wire circuit to operate the selective devices and to hold said contacts in closed position to close 55 the station connecting circuit for a limited period of time after the operation of the selective device, to thereby maintain the signal locking means in unlocked position during said limited period of time to permit 60 the operation of the signal within such time only, and to automatically separate said contacts to open the station connecting circuit and thereby cause the signal locking means to return to locked position. 65

9. In a signal system, a signal and means for operating the same, electrically controlled means for locking and unlocking the signal operating means, apparatus placed at a distance from the signal and electrically 70 connected with said locking and unlocking means and adapted to transmit electrical impulses to control the operation of the signal locking means and to maintain said locking means in an unlocked position for 75 a limited period of time and release said locking means after said impulses have been transmitted.

10. In a signal system, a signal and means for operating the same, means for locking 80 the signal in several different positions against operation in one direction, electrically controlled means for controlling said locking means, a line wire, and a branch circuit including said electrically controlled 85 means, and an apparatus arranged at a distance from the signal and connected with said line wire adapted to transmit electrical impulses to said electrically controlled means to unlock the signal operating means 90 and to close the circuit to maintain the locking means in an unlocked position for a limited period of time and to open the circuit to release said locking means after said impulses have been transmitted, and a 95 controller operated by the signal operating means to open the circuit when said signal operating means is moved.

JAMES W. MURPHY.
